UNITED STATES PATENT OFFICE.

WILLIAM C. MEYER, OF BEVERLY, MASSACHUSETTS, ASSIGNOR TO UNITED SHOE MACHINERY CORPORATION, OF PATERSON, NEW JERSEY, A CORPORATION OF NEW JERSEY.

SEWING-MACHINE.

1,391,398.

Specification of Letters Patent. Patented Sept. 20, 1921.

Original application filed May 6, 1916, Serial No. 95,893. Divided and this application filed September 6, 1918. Serial No. 252,969.

To all whom it may concern:

Be it known that I, WILLIAM C. MEYER, a citizen of the United States, residing at Beverly, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

This invention relates to sewing machines and, more particularly, to thread tension devices for such machines.

15 The invention constitutes an improvement in tension devices of the type comprising a tension wheel about which the thread passes, and a friction brake for retarding the rotation of the tension wheel. The invention is designed particularly as an improvement in tension devices of the form disclosed in the patent granted to present applicant, No. 1,160,936, dated November 16, 1915, but certain features thereof may 20 be embodied with advantage in other forms of tension devices. The invention is illustrated in this application as applied to a chain-stitch sewing machine for sewing the inseams of shoes, but it is also applicable to 25 other classes of sewing machines.

The primary object of the invention is to produce an improved tension device of the above mentioned type in which a uniform braking action of the brake mechanism is 35 secured without attention on the part of the operator regardless of wear on the parts of said mechanism.

With this object in view, the inventor contemplates as a feature of the invention the 40 provision of mechanism for producing automatically a relative adjustment of certain of the parts of the brake mechanism to compensate for wear on the parts.

Other features of the invention consist in 45 certain novel and improved constructions, arrangements and combinations of parts hereinafter described and particularly pointed out in the claims, the advantages of which will be readily understood and appreciated by those skilled in the art.

The invention will be readily understood from the accompanying drawings illustrating the invention in its preferred form, and the following detailed description of the constructions therein shown.

55 In the drawings, Figure 1 is a view in side elevation of an inseam shoe sewing machine embodying the invention looking from the left side of the machine; Fig. 2 is a view in side elevation of the machine looking from the right; Fig. 3 is a detail view in side elevation illustrating the tension devices; Fig. 4 is a detail sectional view taken substantially on the line 4—4 of Fig. 3; Fig. 5 is a detail sectional view taken substantially on the line 5—5 of Fig. 3; Fig. 6 is a detail view partly in elevation and partly in section illustrating certain parts of the tension mechanism; Fig. 7 is a detail view illustrating certain parts of the tension mechanism; and Fig. 8 is a detail view illustrating certain parts of the mechanism shown in Fig. 7.

The machine illustrated in the drawings is a welt shoe sewing machine constructed 75 and arranged for sewing the welt and upper to the insole of a lasted shoe. The machine is provided with a curved hook needle 2, a curved awl 4, a thread arm 6, a looper 8, a take-up 10, an auxiliary take-up 12 and a 80 welt guide 14. All these and other operating parts of the machine are actuated from a main shaft 15. To this shaft is applied a stopping mechanism which operates upon the disconnection of the main shaft from the 85 main driving mechanism, first to arrest the forward rotation of the shaft, then to impart a reverse rotation thereto, and finally to bring the shaft to rest in a predetermined position.

90 All of the parts of the present machine briefly described above have the same construction, arrangement and mode of operation as the corresponding parts of the machine illustrated and described in applicant's co-pending application, No. 95,893, filed May 6, 1916, of which the present application constitutes a division, and reference may be had to said application for a 95 full and complete description of the same.

The machine is also provided with a ten- 100

sion governor by which the tension on the thread is automatically varied with any change in the speed of the machine, with locking mechanism for locking the tension 5 wheel from rotation during the stitch setting stroke of the take-up, and with tension release mechanism for relieving the thread of tension upon stopping the machine. The tension mechanism has the same general 10 construction and mode of operation as the tension mechanism disclosed in the patent granted to the present applicant, No. 1,160,936, dated November 16, 1915, except that there is no variation in the tension produced 15 during each cycle of operations.

The tension devices of the machine illustrated comprise a tension disk 16 around which the thread passes on its way from the supply to the work. The disk is provided 20 with peripheral projections extending alternately in opposite directions from the disk, and being formed at an inclination to the radial lines of the disk to cause the thread to be drawn down to the base of the 25 projections and to enable the thread to free itself readily from the disk. To cause the thread to be drawn down into the passage-way formed by the projections on the disk 16, an auxiliary tension wheel 18 is provided, this wheel being mounted at the rear 30 of the machine, as shown in Fig. 2. The hub of the tension wheel 18 is engaged by a friction washer 20 (see Fig. 7) which is pressed against the hub of the tension wheel 35 by means of a sleeve 22 surrounding the stud 24 on which the tension wheel is mounted, and acted upon by a coiled spring 26 interposed between the sleeve and a collar or nut on the stud. The thread passes 40 from the wax pot 28 of any suitable construction upwardly around the tension wheel 18, through the thread tube 30 around the tension disk 16, under the auxiliary take-up 12, over the main take-up 10 and through the 45 eye of the looper 8 to the work. The resistance exerted by the auxiliary tension wheel 18 to the forward movement of the thread causes the thread to engage the tension wheel 16 tightly as soon as any strain is 50 exerted upon the thread between the tension wheel 16 and the work, so that the thread is at once prevented from slipping around the tension disk 16 and the stitches at the beginning of the seam are sewn under full 55 tension strain.

The tension disk 16 is rigidly secured to one end of a short hollow shaft 32 mounted to turn in a bearing in a bushing or sleeve 34 secured in the frame. To the opposite 60 end of the shaft 32 is rigidly secured a brake drum 36. Arranged to bear on the periphery of the brake drum are two brake shoes 38 and 40 having linings of felt indicated at 42 contacting with the exterior surface of 65 the drum. The lower brake shoe 40 is piv-

otally connected with the end of an arm 46 pivoted at 48 on the frame. The brake shoes are pivotally connected by means of a pin or stud 50, and the shoes are held in proper relation to the drum by means of a 70 spring 52 coiled about the stud and having its ends bearing respectively on the brake shoes, as shown in Fig. 3. The brake shoes are forced into engagement with the periphery of the brake drum by the downward 75 pressure of a lever 54 pivoted at 56 to the frame and having a clutch connection with the upper brake shoe. This clutch connection comprises a rod 58 pivotally connected at 60 with one end of the upper brake shoe, 80 and extending upwardly through an aperture in a block 62 mounted on trunnion pins 64 in an opening in the lever 54. A clutch roll 66 is mounted in the block 62 between a flat surface formed on the rod 58 and a relatively inclined surface formed in the block 62. A coiled spring 68 is mounted in the block below the roll, and acts to force the roll against the flat surface of the rod 58 to clutch the rod to the block 62. When downward pressure is exerted on the lever 54, the block 62 is clutched to the rod 58, and the pressure is transmitted through the rod to the brake shoes. The lever 54 is lifted to release the tension upon the reversal of the 95 direction of rotation of the cam shaft as the machine is stopped, and in order to insure the disengagement of the clutch roll 66 from clutching engagement with the rod 58 when this occurs, a rod 70 is adjustably 100 mounted in the frame in a position such that its lower end will engage the clutch roll 66 when the lever 54 is lifted. The rod 70 is threaded into the frame, and is provided at its upper end with a milled disk 72 by 105 which it may be turned to adjust its lower end. With this clutch connection between the lever 54 and the brake shoe 38, the pressure delivered from the lever 54 through the rod 58 to the brake shoes will be unchanged 110 by variations in the position of the upper brake shoe, resulting from the wearing away of the brake shoe linings or from any other cause. The lever 54 is engaged by an abutment 74 carried by a slide 76 mounted 115 to slide longitudinally in a lever 78 pivoted at 80. This slide is provided with rack teeth meshing with the teeth of a segment formed on a hand lever 82 pivoted at 84 on the lever 78, the hand lever being provided with a 120 spring-pressed pin 86 arranged to engage the teeth of a segment 88 to hold the lever in adjusted position. The lever 78 is pressed upon by a spring-pressed pin 90 having its lower end engaging the lever, 125 and acted upon by a coiled spring 92 coiled about the pin and engaging at its respective ends a collar on the pin and the lower end of an abutment sleeve 94 mounted in the forwardly extending arm of a lever 96 through 130

which sleeve the pin 90 passes. The lever 96 is pivoted at 98, and has its rear end acted upon by a governor mechanism which acts through the lever to vary the pressure 5 of the pin 90 on the lever 78 as the speed of the machine varies. This governor mechanism (see Fig. 6) comprises weights 100 mounted on levers 102 pivoted at 104 on a rotary sleeve 106, the upper inturned 10 ends of which levers are arranged to engage a collar or flange formed on a slide 108 mounted to slide longitudinally on the upper end of a shaft 110, and having an upwardly projecting pin 112 formed thereon 15 which engages the under side of the rear end of the lever 96. The slide 108 is engaged by a coiled spring 113 interposed between a collar on the slide and an adjustable collar threaded upon the shaft 110. The 20 shaft 110 is mounted to turn in suitable bearings in the frame of the machine, and carries at its lower end a beveled gear 114 meshing with a beveled gear 116 mounted on the main shaft 15 of the machine. The 25 sleeve 106 is mounted on the shaft 110 and secured to rotate with the shaft by means of a pin 118. During the operation of the machine the sleeve 106 is rapidly rotated through its connection with the main shaft 30 of the machine, and the weights 100 are swung outwardly from the axis of the sleeve, causing the inturned ends of the levers 102 to depress the slide 108 to an extent varying with the speed of the machine. 35 The variations in the positions of the slide 108 cause variations in the pressure with which the pin 90 engages the lever 78, and this results in variations in the tension applied to the thread, the tension on the thread 40 increasing as the speed of the machine decreases, and decreasing as the speed of the machine increases.

The means for locking the tension disk from rotation when the take-up reaches the 45 limit of its loop-drawing stroke, so as to prevent overthrow of the tension at the end of the pulling-off operation, in the construction illustrated comprises a brake band 120 surrounding the brake drum 36. One end 50 of the brake band is pivoted at 122 to the frame of the machine, and the other end is formed with a socket 124 in which engages the lower end of a rod 126. This rod passes at its upper end through a sleeve 128 (see 55 Fig. 1) mounted in a block 130 pivoted to the forward end of an arm 132. A spring 134 surrounds the rod and is interposed between a collar on the rod and the lower end of the sleeve 128. With this construction 60 the downward swinging movement of the arm 132 will compress the spring and actuate the rod 126 to bring the brake band into locking engagement with the brake drum. The movement of the rod 126 in the sleeve 65 128 under the action of the spring is limit-

ed by the engagement of the stop nut 136 threaded on the upper end of the rod with the upper end of the sleeve 128. Upon the return movement of the arm 132 from tension locking position the movement of the 70 sleeve after it engages the stop nut lifts the rod from engagement with the lower end of the socket in the brake band, allowing the brake band to free itself from the brake drum. The arm 132 is fast upon a rock 75 shaft 140 upon which is mounted a second arm 142 arranged to be engaged by the arm 144 of the take-up actuating cam lever 145.

To relieve the thread of tension when the machine is stopped, the machine illustrated 80 is provided with a tension release mechanism which, when the direction of rotation of the cam shaft is reversed, releases the brake shoes 38 and 40 from braking engagement with the brake drum 36, and also moves the 85 sleeve 22 to release the pressure of the friction washer 20 on the hub of the tension wheel 18. The tension release mechanism comprises a swinging arm 146 such as is ordinarily employed in tension release mechanisms adapted to be operated by a reversal in the direction of rotation of the cam shaft. This arm is pivotally connected to the arm 147 of a lever 148 pivoted at 150 on the machine frame. This lever is provided with a 90 second arm 152 (see Fig. 3) having a socket in which engages the lower end of a rod 154 which has its upper end engaged in a socket in the rear end of the lever 54. An adjustable abutment screw 156 is threaded into 95 the arm 152 to engage the lower end of the rod. The lever 148 is provided with a third arm 158 (see Figs. 1 and 3) connected by a link 180 with an arm 162 fixed to one end of the rock shaft 164. Fixed to the opposite 100 end of this rock shaft (see Fig. 2) is a bell crank lever 166, through the upper arm of which passes a rod 168, the rod having a collar or head 170 at its lower end which engages the upper arm of the bell crank. This 110 rod passes at its upper end through the horizontal arm of a second bell crank 172 pivoted at 174 on the frame, and a stop nut 176 is threaded on the rod to engage the upper side of the arm. The forked upper end of the upper arm of the latter bell crank embraces the sleeve 22 and carries threaded pins 178 engaging in grooves formed in the sleeve. When the arm 147 of the lever 148 is swung forwardly by the movement of the 115 arm 146 upon the reversal of the direction of rotation of the cam shaft, the lever 54, through the engagement of the rod 154 therewith, is lifted to relieve the pressure of the brake shoes on the brake drum. At the 120 same time, through the link 180, the arm 162, the rock shaft 164, the bell crank 166, and the rod 168, the bell crank 172 is actuated to move the sleeve 22 outwardly from the hub of the tension wheel 18, and thus re- 125 130

lieve the pressure of the washer 20 on the hub of the tension wheel.

Having explained the nature and object of the invention, and having specifically described the invention in its preferred form, what is claimed is:

10 1. A tension device for sewing machines having, in combination, a tension wheel, a brake for the tension wheel, a brake actuating spring, operative connections between the spring and the brake, and means for automatically adjusting relatively certain of said connections to cause the spring to act with a pressure which is uniform for any given speed of the machine regardless of 15 wear on the parts of the brake.

20 2. A tension device for sewing machines having, in combination, a tension wheel, a brake acting on the tension wheel, a member arranged to apply tension pressure to the brake, means for actuating said member to relieve the pressure on the brake, and a variable connection between said member and the brake arranged to be adjusted automatically during the tension relieving and applying movement of said member to cause said member to act with a pressure which is uniform for any given speed of the machine regardless of 25 wear on the parts of the brake.

30 3. A tension device for sewing machines, having, in combination, a tension wheel, a brake acting on the tension wheel, a movable member through which pressure is applied to the brake, means for applying tension pressure to said member which is uniform for any given speed of the machine, a variable connection between said movable member and the brake, and means for automatically adjusting the parts of said connection to compensate for wear and thereby secure a correspondingly uniform braking 35 action of the brake.

40 4. A tension device for sewing machines, having, in combination, a tension wheel, a brake acting on the tension wheel, a movable member through which pressure is applied to the brake, means for applying tension pressure to said member which is uniform for any given speed of the machine, a clutch connection between said member and the brake, and means for automatically adjusting the parts of said clutch connection to compensate for wear and thereby secure a 45 correspondingly uniform braking action of the brake.

50 5. A tension device for sewing machines, having, in combination, a tension wheel, a brake for the tension wheel comprising a 55 brake shoe, a rod connected with the brake shoe, a movable member through which pressure is applied to the brake shoe, means for moving said member to release and apply the brake, a clutch connection between the 60 rod and said member, and clutch controlling

means to cause the clutch to clutch the rod always at the same point in the movement of said member.

6. A tension device for sewing machines, having, in combination, a tension wheel, a 70 brake for the tension wheel comprising a brake shoe, a rod connected with the brake shoe, a movable member through which pressure is applied to the brake shoe, means for moving said member to release the brake upon stopping the machine, and to apply the brake upon starting the machine, a clutch connection between the rod and said member, and clutch controlling means for causing the clutch to clutch the 75 rod always at the same point in the movement of said member.

7. A tension device for sewing machines, having, in combination, a tension wheel, a 80 brake drum, pivotally connected brake shoes arranged to engage the brake drum, a rod connected with one of said shoes, a lever by which pressure is applied through the rod to the brake shoes, means for actuating the lever to relieve the pressure of the brake 85 shoes on the drum and to apply braking pressure to the drum, a roll clutch connection between the lever and the rod, and clutch controlling means to cause the clutch to clutch the rod always at the same point 90 in the movement of the lever.

8. A tension device for sewing machines, having, in combination, a tension wheel, a 95 brake for the tension wheel, a governor operating during the operation of the machine to produce variations in the action of the brake to vary the tension on the thread when the speed of the machine varies, a variable connection between the governor and the brake, and means for automatically adjusting the parts of said connection to compensate for wear.

9. A tension device for sewing machines, having, in combination a tension wheel, a 100 brake for the tension wheel, a spring acting on the brake, an abutment for the spring, a governor operating during the operation of the machine to move said abutment to vary the tension of the spring when the speed of the machine varies, a variable connection between the spring and the brake, and means for automatically adjusting the parts of said connection to compensate for wear.

10. A tension device for sewing machines, having, in combination, a tension wheel, a 110 brake for the tension wheel, means for applying pressure to the brake comprising a lever, a spring acting on the lever, a movable member, an abutment carried by the 115 lever arranged to bear on said member and adjustable longitudinally of the lever to vary the tension on the thread, a variable connection between said member and the 120 brake, means for automatically adjusting the parts of said connection to compensate for wear.

85

the parts of said connection to compensate for wear.

11. A tension device for sewing machines, having, in combination, a tension wheel, a 5 brake for the tension wheel, means for applying pressure to the brake comprising a movable member, means exerting pressure on said member in one direction to apply

braking pressure to the brake, means for moving said member from and toward brake- 10 pressing position, and a clutch connection between said member and the brake arranged to be automatically adjusted to compensate for wear by the movement of said member.

WILLIAM C. MEYER.
